UNITED STATES PATENT OFFICE.

AUGUSTUS LACHAPELLE, OF HICKSVILLE, OHIO.

SAND-BAND FOR VEHICLES.

SPECIFICATION forming part of Letters Patent No. 623,791, dated April 25, 1899.

Application filed October 21, 1898. Serial No. 694,230. (No model.)

To all whom it may concern:

Be it known that I, AUGUSTUS LACHAPELLE, a citizen of the United States, residing at Hicksville, in the county of Defiance and State of Ohio, have invented certain new and useful 5 Improvements in Sand-Bands for Vehicles; and I do hereby declare the following to be a full, clear, and exact description of the invention, such as will enable others skilled in the 10 art to which it appertains to make and use the same.

My invention relates to sand-bands for vehicles; and its object is to provide a device of this character which shall be simple and 15 inexpensive in construction, but effective and convenient in use.

The features of the invention will be fully described hereinafter and are illustrated in the accompanying drawings, in which—

20 Figure 1 is a central vertical section through one end of a vehicle-axle and a hub mounted thereon, said axle and hub being provided with my improvements; and Fig. 2 is a transverse section on the line $x-x$ of Fig. 1, showing the means for securing the protecting-band upon the axle.

The reference-numeral 1 designates a portion of an axle provided with an integral spindle 2, threaded at its outer end 3, and 30 with an annular shoulder 4, serving as a stop for the inner end of the hub 5. The protecting-band of the device comprises a ring 6, adapted to fit upon the axle, and an outwardly flared collar 7, formed integral with the ring 35 6. The ring 6 fits upon the axle on the inner side of the shoulder 4 and is held thereon preferably by keys 8, driven between the squared sides of the axle and the inner surface of the ring, the inner side 9 of the shoulder being beveled to serve as stops for the 40 outer ends of the keys 8.

The collar 7 is provided with an integral projecting wing 15, serving as a scraper to scrape mud from the space between the hub 45 and band.

The inner end of the hub is provided with an annular flange 10 to extend over the sand-

band and is recessed to form a central depression 11 around the bore and an annular depression 12 concentric with the flange 10, 50 the portion of the material between said depressions 11 and 12 constituting a guard 13, which projects within the flared collar 7 of the band, the outer edge of the latter extending into the depression 12, while the shoulder 4 on the hub enters the central depression 11.

The outer end of the hub is annularly recessed or countersunk around the bore to receive the nut 14, which is screwed onto the 60 threaded end 3 of the spindle.

It will be clear from the foregoing description that the hub-bearing is fully protected against the entrance of sand or dust, and hence will revolve freely when properly lubricated.

Having thus fully described my invention, what I claim is—

1. The combination with a vehicle-axle provided with a shoulder, of a sand-band comprising a ring fitting upon the axle, and an 70 integral annular flaring collar provided on its outer side with a radially - projecting scraper, and a hub, the inner end of which is provided with a central recess for said shoulder, an annular recess for the edge of the collar and scraper, and a flange to overlap said 75 collar.

2. The combination with a vehicle-axle provided with an annular shoulder, of a sand-band comprising a ring fitting upon said axle 80 on the inner side of said shoulder and an integral flaring collar, provided with a wing or scraper, keys for securing said ring upon the axle, and a hub the inner end of which is provided with a central recess to receive said 85 shoulder, an annular recess to receive the edge of the collar, and a flange projecting inwardly over the sand-band.

In testimony whereof I affix my signature in presence of two witnesses.

AUGUSTUS LACHAPELLE.
